UNITED STATES PATENT OFFICE.

GEORGE MARSHALL, OF LOS ANGELES, CALIFORNIA.

NAIL-STRIPPER.

1,286,698.

Specification of Letters Patent.

Patented Dec. 3, 1918.

Application filed May 2, 1918. Serial No. 232,086.

To all whom it may concern:

Be it known that I, GEORGE MARSHALL, a citizen of the United States, residing at Los Angeles, in the county of Los Angeles and State of California, have invented new and useful Improvements in Nail-Strippers, of which the following is a specification.

This invention pertains particularly to a nail stripper having a hopper and a runway provided with a cut-off leading therefrom. The invention resides particularly in the runway, and the primary object thereof is to provide a nail stripper in which the wastage in assembling the nails for use is a minimum.

More particularly, it is an object of this invention to provide a nail stripper with a runway having means to hold back the nails as they approach the cut-off, so that their speed will be checked and they will jump the runways with substantially no wastage at this point.

It is another object of this invention to provide a nail stripper having a runway so constructed that the jar of nailing will assist in feeding nails slowly into the assembling portion of the runway.

I accomplish these objects by means of the embodiments of my invention illustrated in the accompanying drawing, in which:

Figure 1 is a side elevation of a complete nail stripper. Fig. 2 is a fragmentary plan view on an enlarged scale of a portion of the lower trough and the runway. Fig. 3 is an enlarged section as seen on the line 3—3 of Fig. 1. Fig. 4 is an enlarged section as seen on the line 4—4 of Fig. 1. Fig. 5 is an enlarged fragmentary plan view of the runway showing the hold-back. Fig. 6 is a side elevation of Fig. 5. Fig. 7 is an enlarged side elevation of the assembler. Fig. 8 is a plan view of Fig. 7. Fig. 9 is a section as seen on the line 9—9 of Fig. 7. Fig. 10 is a detail plan view showing the means for adjusting the rails of the upper portion of the runway.

The nail stripper is of the portable type, and so constructed that it may be taken down and placed in a carrier. The carrier serves as a base and comprises a body 11 and cover sections 12 and 13. As these form no part of my invention, they will not be further described.

Supported upon the base by means of adjustable standards 15 and 16 is a hopper 14. The standards are duplicated on the op-

posite side of the stripper. The hopper is inclined so as to feed nails into a trough 17. Secured to the hopper by means of a bracket 18 is a vibrator 19. A battery of cells 20 supplies energy to the vibrator, and the flow of current is controlled by a switch 21. This switch is preferably a push button and may be installed on the bench at any point convenient for use by the box maker.

The trough 17 is pivotally supported at one end upon the standard 16 so that its inclination may be adjusted. The forward end has a link 18' pivotally secured thereto, and pivoted to link 18' is a link 19'. The joint between links 18' and 19' may be fixed by means of a nut 20'. The end of the link 19' is provided with a slot 21'. A bolt and nut 22 disposed on standard 16 and extending through slot 21' serves to secure link 19' to standard 16. It is obvious from the construction just described that trough 17 may have its inclination adjusted. In order to make the construction more stable, the standards and links are duplicated upon the opposite sides of the stripper. The trough 17 comprises aprons 23 and 24 extending to a V shaped bottom consisting of side walls 25 and 26 which are spaced to form a slot 27. At the head end of the slot 27 is a starter 28, which consists of a strip overlying the slot and secured to walls 25 and 26. Nails pass from the hopper into the trough, finally reaching the slotted portion thereof.

Rails 29 and 30 are disposed at the slot 27 and form a runway for the nails. They are adjustable to and from each other to vary the width of the slot and accommodate the stripper to nails of different sizes. Extending between the standards 16 is a bar 31. Referring more particularly to Fig. 10, bar 31 has two longitudinally elongated openings 32 and two transversely elongated openings 33. Bar 30 is provided with bolt holes for registering with the opening 32. It is obvious that rail 30 may be adjusted transversely of itself. Bar 29 has two bolt holes registering with openings 33 so that it may be adjusted longitudinally of itself for a purpose later described. The rails 29 and 30 are secured in their adjusted position by tightening the bolts which fasten them to the bar 31.

Referring particularly to Figs. 5 and 6, it will be seen that bar 29 is reduced in thickness at the end where it is curved, as indicated at 34. An extension 35 is secured

thereto by means of a bolt 36. The rail 30 is turned backwardly so that the runway has a backward bend. The bolt hole in rail 34 is elongated so that extension 35 may be adjusted with respect to rail 30, and thereby the width of the slot in the runway to conform at its lower end with its width at its upper end. Rail 30 and extension 35 end above an assembler.

10 The assembler consists of rails 36 and 37 disposed in alinement with rail 30 and extension 35. The space between the runway and assembler provides a cut-off. Secured to a link 18 is a support 38 which has an arm 39 at its lower end extending transversely. Secured to the arm 39 by means of a bolt is an angle plate 40. Bolt holes are provided in the angle plate 40 for securing the rails 36 and 37 thereto. The bolt holes for rail 20 36 are elongated transversely of the rail for adjustment of the rails 36 and 37 to and from each other to vary the width of the slot therein. Bolts are passed through registering holes in the rails 36 and 37 and the angle 40. A starter 41 which has a beveled edge is disposed across the slot between rails 36 and 37. This starter insures that the heads of the nails will be started so that they are in position to properly overlap one another in the assembler. A series of bolt holes 42 is provided in the support 38 so that the cut-off may be adjusted as to distance. It will be also noted from Fig. 8 that the bolt hole in angle member 40 30 which registers with the bolt hole in arm 39 is elongated to provide for transverse adjustment of the assembler and alinement with the runway. Referring particularly to Figs. 1 and 4, it will be noted that the runway has a dip at the curve therein as indicated by 44. This curve and dip provides a hold-back for the nails as they move down the runway.

40 Nails are placed in the hopper 14, and when it is desired to feed the same to the runway, the vibrator 19 is operated. This jars the hopper and starts the nails, which fall into trough 17. As they move along the trough they enter the V shaped portion 50 at the head end, the points entering the slot

in the runway. The nails then slide down the runway to the hold-back 44, where their speed is checked. They then pass out through the hold-back with less speed and more stability. They next jump the cut-off and pass into the assembler. As the first nail reaches the end of the runway in the assembler, its head overlaps the starter 41. This disposes the first nail in its proper position. The next nail will dispose itself with its head overlapping the first nail. This continues until the nails have filled the assembler, from which they are withdrawn by the box maker.

The stripper is usually placed upon the 65 table where the box maker is working. Each stroke of the hammer jars the stripper. It is possible to so adjust the stripper that nails will pile up in the runway back of the hold-back, and will start down the hold-back one 70 at a time upon each stroke of the hammer. In this way the nails are fed slowly one at a time as the box maker needs them.

What I claim is:

1. A nail stripper comprising an inclined 75 runway having a laterally curved dip therein intermediate its ends to provide a hold-back for checking the flow of nails.

2. A nail stripper comprising an inclined 80 runway for nails having a dip therein to provide a hold-back for checking the flow of nails and a cut-off beyond said dip for withdrawing nails, said dip and cut-off being disposed intermediate the ends of the runway.

3. A nail stripper comprising an inclined 85 runway for nails having a laterally curved dip therein to provide a hold-back for checking the flow of nails and a cut-off.

4. In a nail stripper, a runway for nails comprising two rails adjustable to and from each other, said runway having a return 90 curve therein, an extension at said curve adjustably connected to one of said rails to provide for adjustment of the slot beyond 95 said curve, and a cut-off.

In witness that I claim the foregoing I have hereunto subscribed my name this 23rd day of April, 1918.

GEORGE MARSHALL.
